UNITED STATES PATENT OFFICE.

MICHAEL McCANN, OF GLENMORRIS, NEW YORK, ASSIGNOR TO FREDERICK OSANN COMPANY, OF NEW YORK, N. Y., A CORPORATION OF NEW YORK.

THREAD PULLER FOR AUTOMATIC STOP SEWING MACHINES.

Application filed May 16, 1925. Serial No. 30,752.

To all whom it may concern:

Be it known that I, MICHAEL McCANN, a citizen of the United States of America, residing in Glenmorris, L. I., in the county of Queens and State of New York, have invented certain new and useful Improvements in Thread Pullers for Automatic Stop Sewing Machines, of which the following is a true and exact description, reference being 10 had to the accompanying drawings, which form a part thereof.

My invention relates to sewing machines having automatic stop mechanism such as, for instance, the machine of my former 15 Patent, Number 1,483,185 of February 12, 1924. In machines of this kind the threads are cut or broken close to the needle eyes when the machine is stopped at the completion of a button hole and on restarting the 20 machine there is a liability for the threads to pull out of the needle eyes. The object of my present invention is to provide such machines with a movable tension device located close to the needles and movable substantially parallel to the needles and with 25 means actuated in timed relation to the stopping and starting of the machine whereby the tension device is, immediately before the stopping of the machine, moved upward so as to engage the threads at more elevated 30 points, and whereby also the tension device is moved downward as the machine is started so that there is a free length of thread above the needles which is carried down by the 35 needles without frictional resistance.

Generally speaking, my invention consists in mechanism for effecting this object which in its preferred detail will be best understood as described in connection with the 40 drawings which illustrate my improved mechanism as applied to the machine of my former patent and in which.

Figure 1 is a side elevation of the head of the machine with my improved device 45 applied to it.

Figure 2 is a plan view of mechanism shown in Fig. 1.

Figure 3 is a front elevation of the head showing my tension device in its normal 50 lower position.

Figure 4 is a similar view showing the tension device in elevated position.

Figure 5 is a plan view showing on a larger scale the tension device and the means

for actuating it by the movements of the 55 pull off rod Q⁴.

Figure 6 is a sectional plan view similar in the parts shown to Fig. 3 of my former Patent 1,483,185, and illustrating the stop motion and the correlated mechanism for 60 actuating the pull off rod Q⁴ and,

Figure 7 is a sectional elevation on line 7—7 of Fig. 6.

A indicates the casing enclosing the lower portion of the machine; A' the upwardly 65 extending portion of the casing. A², the horizontal portion and A³ the head proper. C', see Figures 6 and 7, is a downwardly extending rib in the casing portion A. D is the main driving shaft. D', is a hub extension of casing A to provide a sufficient bearing for shaft D. D² is a disk having the general construction described in my former 70 Patent 1,483,185. D⁵ and D⁶ are fast and loose pulleys on the shaft D. D⁷, an eccentric secured to this shaft. D⁸ and D¹⁰, cams secured to the shaft D as in my said former 75 patent. E², a rock shaft actuated as described in my former patent, from the eccentric D⁷ and actuating, through the lever E³, the needle bar E⁴, to the lower end of which are secured the needles indicated at E⁵. G is a rock shaft actuated as described in my former Patents 1,483,185 and 1,461, 80 428, and by means of which an oscillating, reciprocating movement is given to the 85 guide G² in which the needle bar E⁴ reciprocates. F' is a shaft driven from the shaft D through gears, one of which is indicated at F and having attached to it a cam F² 90 which engages the forked end F⁴ of the pivoted block fully shown and described in my said former patents. I is a shaft which, as shown in my former Patent 1,483,185, has secured to it the cams I⁵ and I⁶, the first 95 cam interacting with the lever ends F⁴ and the second interacting with the lever K⁴ and rod K³, all as described in my said former patent.

M is the stop shaft of the machine having 100 buffers M⁴ and M⁵ secured to it which limit its longitudinal sliding motion. M' is a forked lever arm secured to the shaft M and carrying the stop finger M². M³ is a belt shifting arm, m³ being the belt and M⁸ 105 a spring acting to press the shaft M toward the right, as shown in Fig. 6. N is an arm pivoted on the shaft M and carrying a pin

indicated at N' and having an extension N^2 which is engaged, as described in my former patent, by the ends P^4 of the lever P . O is a pivot secured to the frame of the machine on which is pivotally secured the hook O' normally pressed into position to engage the pin N' by the spring O^2 . M^8 is a spring normally tending to move the shaft M toward the right and at M^9 I have indicated a usual 10 crank lever by which the shaft M is shifted toward the left in starting the machine. Q is an arm also pivoted on the shaft M having a portion Q' which engages with cams D^9 and D^{10} , as described in my former patent, 15 this arm also having a laterally extending arm Q^2 which extends beneath the lower end of the pull off rod, indicated at Q^4 . The arm Q is normally drawn downward by the spring indicated at Q^{11} , Fig. 7, and rests 20 on the adjustable screw, indicated at Q^{12} . The pull off rod at Q^4 , as shown in Fig. 1, has a thread engaging device Q^7 at its top and is normally pressed downward by a spring indicated at Q^6 . The threads indicated at q^3 pass through the tension device indicated at S , under hooks indicated at q' and then through proper guides through a take up device indicated at S' which moves 25 with the small bar E^4 .

30 In all of the above described parts the machine illustrated is the same as the machine of my former Patent 1,483,185, and the operation of the machine is the same, the arm N , at the completion of the sewing of a button-hole, being pressed downward so as to disengage the hook O' whereupon the shaft M moves toward the right until the edge of the portion Q' of the arm Q comes in contact with the side of the cam D^9 . Then, as the 35 cam revolves until its lower portion releases the portion Q' of the arm Q , the shaft M is enabled to complete its right hand movement so that the stop finger M^2 engages the recesses provided in the disk D^2 and stops 40 the machine. Immediately before the machine is brought to a stop the cam D^9 lifts the arm Q and through its laterally extending arm Q^2 lifts the pull off rod Q^4 , pulling off the desired amount of thread between 45 the thread engaging device and the hooks q', q' .

50 Referring now to the features which are new in my present machine, 3 is a rock shaft which I secure in proper bearings and which on its outer end has secured to it an arm 4 carrying on its free end a tension device indicated at 5, through which the threads pass immediately above the needles. Also secured to the shaft 3 is a lever arm 6, having a slot indicated at 7 in its free end which is engaged by a pin 9, attached to arm 8, which is secured in turn to the pull off rod Q^4 .

55 In operation, the normal position of the lever itself and the tension device carried by it, is that shown in Fig. 3. When, through

the described mechanism, the pull off rod Q^4 is raised, the rock shaft 3 is actuated and the arm 4 and tension device 5, rises to the position shown in Fig. 4, the thread sliding through the tension device as it is moved 70 upward. Immediately after the shifting of the position of the tension device, the machine comes to a stop. The machine is started again by shifting the stop shaft M toward the left and as this moves the arm Q so that it is no longer supported on the cam D^9 , this arm at once moves downward, as does also the supported pull off rod Q^4 , with the result that, as, or immediately before, the needles begin to operate, the tension device 5 moves back to the position shown in Fig. 3, so that the needles can move 80 downward to begin the sewing of another button-hole without exerting any pull on the threads. It will be clear that a supply of thread for the downward movement of the tension device is supplied by the downward movement of the takeup element S' (which is fastened to and moves with the needle bar) from its position as shown in 85 Fig. 4 to that shown in Fig. 3.

Having now described my invention, what I claim as new and desire to secure by Letters Patent, is:

1. In a sewing machine having an automatic stop device for arresting the motion of the machine, the combination therewith of a tension device through which the threads pass located close to the needles and movable through a path substantially parallel to the needles, a machine element, means for holding and retracting said element in and to normal retracted position, means connecting the said machine element with the tension device to move it upward when the machine element is moved from normal position and downward when said element returns to normal position, and means moving in coordinated relation to the stop motion actuating mechanism whereby the said machine element is shifted from normal position immediately before the machine is stopped and permitted to return to normal position substantially simultaneously with the starting of the machine. 100

2. In a sewing machine having an automatic stop device for arresting the motion of the machine, the combination therewith of a tension device through which the threads pass located close to the needles and movable through a path substantially parallel to the needles, a pull off device, means for holding and retracting said pull off device in and to normal retracted position, means connecting the said pull off device with the tension device to move it upward when the pull off device is moved from normal position and downward when said pull off device returns to normal position, and means moving in coordinated relation to the starting of the machine. 110

the stop motion actuating mechanism whereby the said pull off device is shifted from normal position immediately before the machine is stopped and permitted to 5 return to normal position substantially simultaneously with the starting of the machine.

3. In a sewing machine having an automatic stop device for arresting the motion 10 of the machine, the combination therewith of a tension device through which the threads pass located close to the needles

and movable through a path substantially parallel to the needles, a vertically extending rod carrying a pull off device at its 15 upper end, means operating in timed relation to the stop motion for elevating the rod just before the machine stops and returning it to normal retracted position as the machine is started, a shaft, means operatively connecting said shaft to the pull off rod and means for actuating the movable tension device operated by said shaft. 20

MICHAEL McCANN.
